UNITED STATES PATENT OFFICE.

PIETRO BIASUCCI, OF YUKON, PENNSYLVANIA.

WINDOW-SHADE.

1,324,421.

Specification of Letters Patent.

Patented Dec. 9, 1919.

Application filed August 14, 1919. Serial No. 317,488.

To all whom it may concern:

Be it known that I, PIETRO BIASUCCI, a citizen of the United States, residing at Yukon, in the county of Westmoreland and

5 State of Pennsylvania, have invented certain new and useful Improvements in Window-Shades, of which the following is a specification.

10 The primary object of the present invention is to provide a window shade that is capable of being raised and lowered to the desired points and effectively retained in adjusted positions to the exclusion of spring devices that are usually employed in window shades of ordinary construction, the window shade being raised and lowered by pull cord devices associated with the curtain and shade roller bar.

15 A further object of the invention resides in the provision of a springless shade roller that is positively raised and lowered by independent pull cord devices, the shade stick coöperating with the bracket bearings of the shade roller for limiting the rising movement of the shade.

20 With the above and other objects in view, the invention consists in the novel form, combination and arrangement of parts herein fully described in connection with the 25 accompanying drawing and in which like reference characters indicate similar parts throughout the several views.

In the drawings,

30 Figure 1 is a fragmentary view of a portion of a window frame with the present invention in operative position thereon,

35 Fig. 2 is a side elevational view of the bearing bracket for supporting the ratchet end of the shade roller bearing partially 40 shown in section and illustrating the spring pressed plunger for engaging the ratchet roller to arrest movement thereof and

45 Fig. 3 is a vertical sectional view through a portion of the bracket shown in Fig. 2, illustrating in side elevation, the reduced end of the shade roller bearing.

50 Briefly described, the present invention aims to provide a window shade that is adapted to be raised and lowered by independent devices to the exclusion of spring elements, *i. e.*, a spring associated with the roller bearing for restoring the same to its initial position or for elevating the shade. In the present device, the roller bearing for 55 the shade extends from opposite sides thereof and is rotatably mounted in bearing

brackets, a spring pressed plunger being associated with one bearing adapted to seat in spaced sockets formed on the periphery thereof while a pulley is attached to the 60 other projecting end of the roller bearing and is adapted to have one end of a cord secured thereto which cord will be wound upon the pulley when the shade is lowered, and it being desired to elevate the shade, it 65 is only necessary to pull the cord wound upon the pulley to rotate the shade roller and wind the shade thereon during which time the spring pressed plunger ratchets over the sockets in the roller bearing and 70 as will be clearly understood, the height of adjustment of the shade may be regulated at the will of the operator as the spring pressed plunger coöperating with the shade roller bearing will hold the window shade in any 75 set position. It is also contemplated that the stick carried by the window shade coöperate with the bearing brackets to arrest the raising of the shade when the projecting ends of the window stick engage the 80 brackets.

Referring more in detail to the accompanying drawing, the reference numeral 5 designates a window frame having a pair 85 of brackets 6 and 7 secured adjacent the upper ends thereof, which brackets form bearings for the ends of the shade roller 8 shown in Fig. 3, and upon which the window shade 9 is secured, a curtain 10 being centrally attached to the shade stick 11 by 90 which the shade may be lowered, the opposite ends of the stick 11 projecting beyond the sides of the shade as at 11' shown in Fig. 1.

The bracket 6 is shown more clearly in 95 Figs. 2 and 3 and is provided with a cylindrical transverse opening 12 within which a metal bearing cylinder 13 is secured, the metallic cylinder 13 forming a bearing for the metallic thimble 14 secured upon the reduced end 8' of the shade roller 8, the thimble being secured upon the shade roller end by a screw 15. As clearly shown in 100 Figs. 2 and 3, the thimble and reduced end 8' of the shade roller are provided with 105 coöperating sockets 16 into which the pointed end 17 of a plunger is adapted to seat, the stem 18 carried by the lower end of the plunger operating in a cylindrical socket or cut out portion 19 in the bracket 6 110 and being surrounded by a coil spring 20 extending between the plunger head and the

lower end of the socket 18, to force the plunger upwardly through an opening in the bottom of the cylinder 14 that registers with the flange recess 19.

5 The opposite end of the shade roller 8 projects outwardly of the bearing bracket 7 as shown in Fig. 1 and has the pulley 21 secured thereto, a spring finger 22 carried by the outer face of the bracket projecting 10 over the pulley to insure a tracting thereon of a pull cord 23 having one end secured to the pulley.

In the operation of the device, assuming that the shade 9 is in the position shown 15 in Fig. 1, the same may be lowered by pulling upon the cord 10 which will cause a rotation of the reduced end 8' of the shade roller with a consequent ratcheting motion of the plunger 17 and the socketed thimble 14, it 20 being understood that the shade is capable of being lowered to any desired point and retained against further downward movement by the spring pressed plunger 17 engaging in the thimble sockets 16. During 25 the lowering movement of the shade, the pull cord 23 being wound upon the pulley 21 and when it is desired to elevate the shade, it is only necessary to pull upon the cord 23 to cause a reverse rotation of the 30 roller bearing 8 against the ratchet devices in the bracket 6 so that the shade may be raised to the desired height. In the raising of the shade, the projecting ends 11' of the shade stick limit the upward movement of 35 the shade by engaging the lower faces 24 of the brackets 6 and 7 as shown by dotted lines in Fig. 2. With this construction of shade roller mount, it will be observed that the roller operates to the exclusion of 40 springs for elevating the shade while the shade is capable of being retained in any adjusted position by the tensioned plunger devices disclosed and also, the raising and lowering thereof is accomplished in an easy 45 and quick manner.

While there is herein shown the preferred embodiment of the invention, it is nevertheless to be understood that minor changes

may be made in the form, combination and arrangement of parts without departing 50 from the spirit and scope of the same as claimed.

What is claimed as new is:—

1. A device of the class described comprising a pair of brackets, a shade roller 55 supported at its opposite ends in said brackets, one of said brackets having a metallic cylinder arranged transversely thereof, a metallic thimble on the adjacent end of the shade roller journaled in said cylinder, sockets formed in said thimble and roller end, the bracket having a vertical socket therein, a spring pressed plunger within said socket adapted to be consecutively seated in adjacent thimble sockets, 60 the other end of the shade roller projecting beyond the other bracket, a pulley secured to the projecting end thereof, a spring finger carried by the last named bracket and overlying the pulley and a cord secured to said pulley for rotating said shade roller.

2. A device of the class described comprising a pair of brackets, a shade roller supported at its opposite ends in said brackets, one of said brackets having a metallic cylinder arranged transversely thereof, a metallic thimble on the adjacent end of the shade roller journaled in said cylinder, sockets formed in said thimble and roller end, the bracket having a vertical socket 75 therein, a spring pressed plunger within said socket adapted to be consecutively seated in adjacent thimble sockets, the other end of the shade roller projecting beyond the other bracket, a pulley secured to the 80 projecting end thereof, a spring finger carried by the last named bracket and overlying the pulley, a cord secured to said pulley for rotating said shade roller, and a shade stick carried by the shade and extending 85 from opposite sides thereof adapted for engagement with the shade roller brackets during the rising movement of the shade.

In testimony whereof I affix my signature.

PIETRO BIASUCCI.
